UNITED STATES PATENT OFFICE.

JOSEPH SACHS, OF HARTFORD, CONNECTICUT.

ELECTRIC SWITCH.

1,297,012.

Specification of Letters Patent. Patented Mar. 11, 1919.

Application filed October 14, 1915. Serial No. 55,784.

To all whom it may concern:

Be it known that I, JOSEPH SACHS, a citizen of the United States, residing at Hartford, in the county of Hartford and State of Connecticut, have invented certain new and useful Improvements in Electric Switches, of which the following is a specification.

This invention relates to electric switches. A switch involving the invention possesses several advantageous features, among them being the provision of a casing in which a switching member may be mounted and an actuator for the switching member associated with the casing in a compact relation and susceptible of easy and ready action, the actuator, in addition to operating the switching member, presenting a means for positively preventing access to the casing when the switching member is on. Another object is the provision of means whereby switching members of different characters can be interchangeably used, either form when in position being securely maintained in such relation. A further point is the provision of a switching member primarily intended to carry one or more inclosed fuses and of such structure that such a fuse or fuses when blown can be readily removed and which when in active position can be substantially held therein. Another object is the provision of a novel form of a toggle mechanism, for imparting to the switching member a snap or accelerated motion. The device possesses other features of improvement which with the foregoing will be stated at length in the following description, wherein I will fully set forth that form of embodiment of the invention which I have selected for illustration in the drawings accompanying and forming part of the present specification. I do not restrict myself to this disclosure; I may depart therefrom in several respects within the scope of the invention defined by the claims following said description.

Referring to said drawings:

Figure 1 is a perspective view of a switch involving my invention, the actuator being in position to prevent access to the interior of the casing.

Fig. 2 is a similar view with the actuator in the off position and the cover of the box or casing partially removed so as to permit access to the interior of the casing.

Figs. 3 and 4 are transverse sections on

the line 3—4 of Fig. 7, looking in the direction of the arrows and showing the parts in the on and the off positions respectively.

Fig. 5 is a front elevation partly in section of the lower portion of the box.

Fig. 6 is a transverse section on the line 6—6 of Fig. 5, showing the cover as being removed.

Fig. 7 is a top plan view of the switch with the cover of the box removed and with the actuator in cross section.

Fig. 8 is a cross section on the line 8—8 of Fig. 7, looking in the direction of the arrows and with the actuator in the off or releasing position and the cover of the box removed.

Fig. 9 is a similar view with the cover of the box applied and with the actuator in the on or cover retaining relation.

Fig. 10 is a section on the line 3—4 of Fig. 7, looking in the direction of the arrows with the actuator in the off position, the cover of the box removed and with the clamp of the inclosed fuse carrier in releasing position to free the fuse or fuses on said carrier, one of which is shown as above the carrier.

Fig. 11 is a detail view partly in section of a switching member and a portion of its support, the connectors of said switching member being removed.

Fig. 12 is an end view of the clamp of the switching member.

Fig. 13 is a section on the line 13—13 of Fig. 11, looking in the direction of the arrows, of the carrier only of said switching member.

Fig. 14 is a detail view of a clamp-locking toggle.

Fig. 15 is a transverse section on the line 15—15 of Fig. 7, looking in the direction of the arrows, the two sides of the view being brought together and the switching member and contacts not showing.

Fig. 16 is a sectional view of a stationary contact and associated wire connecting and holding means.

Fig. 17 is a top plan view of a different form of switching member and the co-operating stationary contacts, a part of the switching member support and boxing being illustrated.

Fig. 18 is a transverse section on the line 18—18 of Fig. 17, looking in the direction of the arrows.

Fig. 19 is a detail view of the second form of switching member attached to the support.

Fig. 20 is a cross section on the line 20—20 5 of Fig. 17, looking in the direction of the arrows, the stationary contacts and the support being omitted.

Like characters refer to like parts throughout the several views, which it will be noted 10 are on different scales.

An electric switch involving the invention comprises a casing or box. This casing or box for protective purposes is adapted to house or inclose a switching member 15 of suitable character and its requisite co-operating contact or contacts, generally stationary. The casing or box, the switching member and the contact or contacts may be of any desirable nature. Preferably the box 20 has a cover, and when the cover is on, the casing or box is closed and may be suitably latched and sealed, a sealable latch of novel construction being provided for this purpose. In conjunction with the switching 25 member is an actuator, and this actuator has in the present case, positions corresponding with those of the switching member, namely on and off positions. I provide means preferably externally of the box and which pref- 30 erably moves approximately in a straight line, for preventing access to the box when the switching member is on or in circuit closing position, said means being governed by the actuator or its associated switching 35 member. This actuator, in the present case, has as a part of it, means disposed in the path of opening movement of the cover of the box, the means in question acting to prevent the cover being taken off when the 40 switching member is on. In the organization illustrated said means is entirely free of the cover, being merely disposed in the path of opening movement of the cover, having in fact no interlocked connection 45 therewith. In some cases there might be a contact between said means and the cover, but this contact is not a matter of consequence, the primary purpose being that there be an abutment in the path of opening 50 movement of the cover. While said means is susceptible of advantageous use in connection with covers mounted in various ways, it is, owing to the functioning of said means in the manner set forth, of particu- 55 lar utility when used in conjunction with a non-pivoted cover, such as one which is bodily removable.

A box meeting my conditions is that denoted in a general way by 2. This box is 60 equipped with a removable cover 3 adapted when closed as shown for instance in Figs. 1, 3 and 4 to fit over the body of the box. The cover or lid 3 as shown is provided in- 65 teriorly with pins as 4 adapted to hook in openings or slots as 5 in one end of the

body of the box shown for instance in Figs. 5 and 6, the cover when closed receiving the slotted tongue 6 (Figs. 1 and 2). The cover 3 as shown is provided with a latch member as 7 pivoted thereto and the operative 70 portion 8 of which is approximately of U-form and may be sealed as will hereinafter appear. When the cover 3 is applied the slotted tongue or catch-piece 6 will project through the slot 9 in the cover at which 75 time one branch of the U-shaped portion 8 can be projected through the slot of the tongue 6, following which a sealing wire may be passed through the perforations of the branches of the U-shaped portion 8 and 80 sealed in any of the ways in common use. It will be observed that the outer branch or leg of the resilient U-shaped or operative portion 8 of the latch 7 is bowed or deflected inwardly, by reason of which when the inner branch of said portion 8 is passed through the slot in the tongue or catch piece 6, said bowed or deflected portion will snap over the catch piece or tongue to thus maintain the latch in its holding relation. While 85 this latching means is of novel construction and well suited for the purpose, it is merely one way of holding a cover in place.

While the actuator which I have shown is one form of push and pull type and has a 90 sliding movement along approximately a straight path, it may not be necessary in all cases that the path be an exactly straight one. An actuator which meets the desired conditions is that denoted in a general way 100 by 10. This actuator is virtually of yoke form, the side arms of the actuator being slidably received in and guided by brackets or loops 11 fastened as by riveting or otherwise exteriorly of the box on opposite sides 105 thereof. The side arms of the actuator are bent inward between their ends to produce detent or abutment portions 12 which are in the path of opening movement of the cover 3 when the switching member is on. In 110 Figs. 1, 3 and 9 the actuator 10 is shown as being in the on position and the inner surfaces of these portions 12 at this time overlie and are contiguous to the cover 3, by reason of which the latter can not be opened 115. nor can it be until the actuator is moved to the off position as shown for example in Figs. 2, 4 and 10. When the actuator is in this position the detent or abutment portions 12 will be sufficiently removed from 120 the cover as to permit the opening of the cover provided the seal already alluded to, if used, be broken and the latch member 7 be swung back as shown in Fig. 2. The transverse portion 13 of the actuator 10, constitutes a grasping, manipulating or handle part. While it is highly advantageous that the actuator should be accessible exteriorly of the box 2, this may not in all cases be necessary.

The switching member, its support and its coating stationary contacts are inclosed in the box 2. The support for the switching member may of any suitable character, that 5 denoted by 14 answering satisfactorily in this connection. This support 14 is of U or stirrup form, its body or transverse portion directly sustaining the switching member, while its end portions 15 are connected to the 10 side arms of the actuator 10. The ends 15 of said support are connected to the side arms of the actuator by screws 16, there being two screws on each side. The sides 15 of the box 2 have vertically elongated slots 17 through which the two pairs of screws 16 project and in which they vertically move.

As already stated I may use in conjunction with a support as 14, or equivalent, any one of several different kinds of switching members, two being shown. One of these switching members is equipped with an inclosed fuse or fuses and the other has a plug fuse or fuses. I will first describe the form of switching member which is furnished with the inclosed fuses. Such a switching member is shown in Figs. 3, 4, 7, 8, 9 and 10, in detail in Fig. 11 and certain of its parts in Figs. 12, 13 and 14. This switching member 18 comprises as illustrated a carrier or main section 19 and a clamp or auxiliary section as 20. The carrier has seats as 21 in its upper side to removably receive the inclosed fuses 22, constituting suitable connectors. The clamping member 20 extends across the tops of the seats or channels 21, and when resting on the upper side of the carrier 19 retains the fuses 22 in their seats 21. To removably hold the switching member to its support as 14, screws as 23 may be provided. These screws are threaded into the support and extend through holes in the carrier 19, the plain cylindrical upper portions, presenting shoulders, acting against the carrier 19 to hold it to the support. These cylindrical plain portions of the screws also act as guides for the clamping member 20 which latter as will be clear moves independently of the screws, separate means being provided for locking the clamping member 20 in active position. To accomplish this particular result, I may as illustrated provide two lockers each of toggle form and consisting of links or members 24 and 25. Each member 24 consists of a yoke-like link pivoted to an end of the clamping member, while each link 25 consists of a preferably curved strap pivoted to the carrier 19 as for instance at 25'. In Fig. 11 the toggle on the left is shown as being in its locking position, the point of connection of the two links being on the inside of the dead center line of said particular toggle. The toggle on the right is in releasing position, the center of connection between the two links

being on the outside of the dead center line thereof. By moving the two toggles to releasing position the clamping member 20 can be elevated so as to lift out a blown fuse (Fig. 10) and replace a fresh one. When the new fuse is positioned, the clamping member 20 will be lowered and the two toggles moved to locking position. 70

The support 14 carries the switching member of whatever form it may be. Where screws are used to attach or fix the switching member to the support, the threaded holes or other means in the support for receiving such screws or other holding down means, are preferably so disposed as to permit the attaching means for any of the various switching means to coat therewith. While this arrangement is desirable and is shown in the construction herein illustrated, it is however, not imperative as each switching member may have separate screw receiving holes or equivalent means.

In the construction shown the said support is connected with the actuator 10 by two pairs of screws, each pair serving to connect an end portion 15 of the support with the adjacent coöperative side arm of the actuator. These two screws disposed one above the other, move in the slot 17 and serve to connect the switching member support and its associated actuating means. They also act to prevent swinging motion in the switching member and assure a substantially straight line movement of the contacting parts. Equivalent means may, however, be provided to accomplish this result. The inner screw of each pair while serving as the pivot connecting the links of each coacting toggle, extends through a hole in its coöperating end portion of the support 14 and is threaded into the adjacent coöperating side arm of the actuator. The outer screw of each pair is threaded into its coöperating end 15 and extends through a hole in the adjacent side arm of the actuator. As shown this arrangement holds the switching member and its associated actuator in substantially fixed relation one to the other. Relative movement of the parts may be obtained by elongating or enlarging the unthreaded holes, in the end 15 of the support and the side arms of the actuator, through which the screw 16 extends.

In conjunction with the switching member and its externally accessible actuating means, there is means for imparting to the switching member an accelerated or snap movement, this being accomplished in the present instance by a toggle. Said toggle imparts to the switching member a quick movement, being tensioned by and on each movement of the actuator and released at predetermined points in the on and off movements of the switching member and

its associated actuating means so as to secure the function in question.

In the construction shown I represent two over-the-center toggles, each having duplicate spring links 26. The outer ends of the links of the two toggles are pivoted to the sides of the box 2 interiorly thereof. The inner ends of the two pairs of links are pivoted to each other by the inner or lower screws 16. I have mentioned the fact that the two toggles have spring links. It will be understood, therefore, that each link is in the form of a spring or resilient. The outer ends of the two links of each toggle in the present case, move about fixed axes and the toggling action is obtained as shown by the springiness or resilience of the links themselves. That is to say nothing extraneous of the links is required to obtain the snap toggle action. In Figs. 8 and 15 for illustration the links 26 of the two toggles are shown as being in their releasing or off positions, the centers of connection of the two links of each pair being above the dead center lines of the two toggles. As the actuator 10 is moved inwardly the centers of connection between the two pairs of toggle links are moved toward and then across the dead center lines. As the centers of connection approach these dead center lines, the toggle links are bowed inward or tensioned, the links being released the instant the dead center lines are crossed so by reaction the spring links can impart to the support 14 and therefore to the switching member 18 carried thereby a snap movement.

While it is true in the construction shown that there is a snap movement of the switching member on the closing movement thereof, this effect is not of the utmost consideration; as a matter of fact the amount of snap movement at such time is quite small. When the switching member is moved to off position, however, or withdrawn from its coacting stationary contacts, the snap movement is greater, by virtue of which arcing is greatly reduced. The amount of snap movement imparted by the spring link toggles in either direction beyond the dead center line will depend upon the relationship between the stops (hereinafter described) for the switching member and the position of the outer ends of the links of each toggle. The movement of the switching member is fixed in the construction shown, by the length of the slots 17 through which the screws connecting the ends of the support 14 and the side arms of the actuator 10 project. These screws striking the ends of the slots in either direction, serve to arrest the movement of the switching member support and consequently the switching member and its connector parts.

While two toggles of the character described are advantageous in that a balanced action is obtained, there may be instances where but a single toggle of this kind could be utilized. This toggle is not restricted in its use or association with a switching member and an actuator such as described. In like manner I am not limited to the use of any particular means for obtaining a snap action as set forth, although the toggles described are highly advantageous.

In the box 2 are stationary contacts as 27 arranged in coöperating pairs. As shown the switch is a three pole-switch and is provided with three pairs of these contacts 27. In other kinds of switches there may be but a single contact or any number of pairs. These contacts 27 are resilient and of practically inverted U-form, being supported by the insulated bases 28 which are rigidly connected in some suitable manner to the bottom of the box. The outer leg or branch of each resilient contact 27, is shown connected as by rivets to an approximately inverted L-shaped wire connecting member 29 which fits over the upper side of its supporting insulating base 28 and is held in place thereto in any desirable manner for instance by the screw 30. As shown the screws carry nuts 31 constituting convenient means for clamping the respective wires to the wire connecting members 29. When the switching member 18 is in the on position, the end ferrules or terminals of the inclosed fuses 22 engage the contacts 27 so as to electrically bridge the contacts of the respective pairs as shown for example in Fig. 9. The box 2 may be provided with wire ducts 32 serving the customary function or any other means may be provided for leading the necessary wires into and out of the box.

Referring now to Figs. 17 to 20 inclusive, the switching member 33 coöperates with the contacts 27 already described or with others of a suitable nature, and is removably carried by the support 14. This switching member 33 is moved to the on and off positions as already described. The switching member 33 has an insulating body 34 of porcelain or other suitable material and is perforated to receive screws as 35 by which said switching member 33 can be detachably connected to the support 14. The insulating body 34 has one or more shells as 36 of screw type held to the body by screws as 37, these screws extending through the insulating body 34 and being threaded into strips 38 bent around one side of the body 34, strips as 39 being bent around the opposite side of said insulating body and being extended into and electrically connected with the respective shells 36. Each shell 36 constitutes a contact and each screw 37 also constitutes a contact. Each strip 38, therefore, presents a continuation of a screw 37, while

each strip 39 constitutes a continuation of each shell 36. Each shell 36 and screw 37 is insulated for example by a fiber washer 40. By the insertion of a fuse plug as 41 into a shell as 36 and the bottoming of the plug in the shell, the shell and coöperating screw 37 will be electrically bridged as will coöperating strips 38 and 39. The terminals of these strips 38 and 39 are adapted, as will be obvious, to slide downward between and against coöperating stationary contacts 27 of a pair, in the same manner as is the case with the other form of switching member. The switching members shown are adapted to receive but two different kinds of fuses. It will be clear that switching members of other kinds and employing different types of fuses may be substituted therefor, and in some cases the switching member might be unfused.

It will be noted that the spring toggle links or equivalent means, in addition to serving as means to impart a quick or accelerated movement to the switching member from the on to the off position and vice versa, also act to hold or position the switching member in such position, so that it will be maintained in each position in proper relation with the stationary contacts which coöperate with the connectors of the switching member. The means for imparting the accelerated movement and for holding the switching member in its on or off positions, is, in the construction shown, the spring toggles, but it is not imperative that this be the case although such an arrangement provides an advantageous construction. The means for holding the switching member in its on and off positions need not essentially act to impart an accelerated movement to the switching member in its travel from one position to the other. It is of importance, however, that the switching member be held in its on and off positions. The spring link toggles are one form of construction to produce this result.

What I claim is:

1. In an appliance of the character described, a box, a cover for said box, a switch in said box, supported independently of the cover, reciprocating actuating means for the switch, accessible exteriorly of the box and comprising means to prevent opening of the cover sufficiently to give access to the switch when the switch is closed and movable in the direction of opening movement of the cover to free the cover.

2. In an appliance of the character described, a box, a cover for said box, a fused switch in said box, supported independently of the cover, reciprocating actuating means for the switch, accessible exteriorly of the box and comprising means for preventing opening of the cover sufficiently to give access to the fused portion of the switch while

the switch is closed and movable in the direction of opening movement of the cover to free the cover.

3. In an appliance of the character described, a box, a cover for said box, a switch in the box involving a movable member carrying a fuse, the switch being supported independently of the cover, reciprocating actuating means for the movable member of the switch, accessible exteriorly of the box, and means to prevent opening of the cover sufficiently to give access to the fused portion when the switch is closed.

4. In an incased fused switch, a box having a cover, a switching member supported in the box and independently of the cover, a fuse electrically associated with the switch, actuating means also independent of the cover and reciprocably movable and having an operative connection with the switching member within the box, the switching member having in turn means coöperatively associated therewith to prevent access to said fuse by the removal of said cover while the switch is in the on position and in the off position to electrically disconnect said fuse from the live parts of the circuit and to permit the opening of said cover for the purpose of giving access thereto, said actuating means being movable in the direction of opening movement of the cover to free said cover.

5. A box, a cover for said box, a switching member in said box, actuating means for said switching member accessible exteriorly of said box and movable along an approximately straight path, said switching member and said actuating means being independent and free of the cover, and means associated with said actuating means and movable in approximately a straight line, for preventing opening of the cover, when the switching member is in the on position.

6. A switch box having a cover, a switch member, actuating means accessible exteriorly of the box and movable in approximately a straight line and independent and free of any connection with said cover, said actuating means when the switch member is in the on position, being in the path of opening movement of said cover.

7. In an incased switch comprising a box having a cover, and a switching member therein movable between on and off positions, actuating means for said switching member accessible exteriorly of the box, said switching member with its associated actuating means being movable in an approximately straight line and being free of any connection with said cover and within the path of opening movement of said cover when the switching member is in the on position.

8. In an incased switch comprising a box and its cover and a switching member mov-

- able in said box, between on and off positions, means accessible exteriorly of the box, for actuating the switching member, said actuating means having means directly associated therewith and moving in an approximately straight line within the path of opening movement of the cover, for preventing the opening of said cover when the actuating means and the switching member are in one of their positions, said two means being movable independently of the cover.
9. A box, a switching member in the box movable between on and off positions, a yoke-like actuator slidably straddling the body of the box, and means connecting the actuator and the switching member and extending through the box, the actuator having an abutment exterior of the box and disposed in the path of opening movement of the cover when the latter is closed and when the switching member is in the on position.
10. A box having a cover, a switching member mounted for sliding movement within said box, a yoke-like actuator slidably straddling the body of the box and connected with said switching member within the box, said actuator being movable toward and from the cover of said box in an approximately straight line and having a portion disposed in the path of opening movement of the cover when the latter is in a closed position and the actuator is in the on position.
11. A box having a cover, a switching member in the box movable along an approximately straight line, actuating means for the switching member accessible exteriorly of the box, free of and movable independently of the cover along an approximately straight line, means movable with the switching member during the on movement thereof, and free and independent of the cover, for preventing opening of the cover when the switching member is in the on position, means for arresting the motion of the switching member when the same is in the on and the off positions, and means for accelerating the motion of the switching member during its respective movements, and for holding the same against accidental reactive movement when in said two positions.
12. An electric switch comprising a switching member, a support for the switching member, an actuator for moving the switching member to on and off positions, and a pair of springs constituting in themselves toggle links, connected at their inner ends to the support, the outer ends of the links being pivoted to a relatively fixed part and the actuator on each of its movements being adapted to tension the spring links and to move their point of connection across the dead center line of the toggle.
13. An electric switch comprising a box, a switching member and its support in said box, of approximately U-form, a yoke-like actuator straddling the box, the side arms of the actuator being connected with said support, two pairs of toggles each having a pair of links in the form of springs connected at their inner ends to said support, the outer ends of the links of the two toggles turning about fixed axes, and the actuator on each of its movements tensioning the springs of the toggles and then moving the inner ends of the links thereof across the dead center lines of said toggles.
14. A switching member comprising a carrier and a clamping member, the carrier having a seat for an inclosed fuse and the clamping member holding the fuse in the seat, and toggles connected with the carrier and with the clamping member and adapted when in one position to maintain the clamping member in fuse holding position.
15. An electric switch comprising a box, a switching member and its support in said box, of approximately U-form, a yoke-like actuator straddling the box, the side arms of the actuator being connected with the support, toggle means associated with said actuator and having spring links movable at their outer ends about fixed axes, the actuator on each of its movements moving the inner ends of the said links across the dead center line.

In testimony whereof I affix my signature in presence of two witnesses.

JOSEPH SACHS.
